UNITED STATES PATENT OFFICE.

THOMAS M. COLLISON AND FREDERICK P. CURRIE, OF ATLANTIC CITY,
NEW JERSEY.

SYSTEM OF EXTINGUISHING FIRES.

SPECIFICATION forming part of Letters Patent No. 740,238, dated September 29, 1903.

Application filed February 10, 1903. Serial No. 142,690. (No model.)

To all whom it may concern:

Be it known that we, THOMAS M. COLLISON and FREDERICK P. CURRIE, citizens of the United States, and residents of Atlantic City, New Jersey, have invented certain Improvements in Systems of Extinguishing Fires, of which the following is a specification.

Our invention relates to certain improvements in fire-extinguishing systems, and more particularly consists in an improved combination of apparatus for extinguishing fires in oil-tanks, the object of the invention being to provide a system of the character described which while possessing the maximum efficiency for use in extinguishing a fire in an oil-tank shall not be subject to injury from lightning discharges. This object we attain as hereinafter set forth, reference being had to the accompanying drawings, in which—

Figure 1 is a diagrammatic view, partly in section, showing our improved system as applied to an oil-tank. Fig. 2 is a side elevation of our improved non-conducting joint with its connected parts, and Fig. 3 is a side elevation of one of the devices for distributing a spray of mixed gas and liquid over the surface of burning oil in a tank.

Hitherto it has been noted that whenever the oil in a tank was ignited by a lightning discharge the oil-supply pipe, as well as any other metallic pipes connected to the tank, was almost invariably destroyed or at least temporarily rendered inoperative by the same agency. It is with the idea of providing a device which shall be practically free from the possibility of such damage that we have devised the system illustrated and hereinafter described.

In the above drawings, A is an oil-tank of the ordinary construction, having in the present instance at the center of its bottom an opening a, to which is connected, by means of suitable flanges, a pipe a', extending nearly to the height of the tank and above the level of the liquid therein, so as to prevent passage of oil through said opening a. Within this pipe are a series of insulating-rings a², through whose central openings extends a pipe B, connected to any desired source of supply (indicated at C) for the generation of liquid or gas capable of extinguishing fires. The up-

per end of this pipe B is provided with any desired number of extended branches b, whose outer ends are supported by means of vertical bars or struts b', carried upon the bottom 55 of the tank A, but insulated therefrom by insulating dishes or blocks b². The free ends of the branch pipes b are turned down and each carries a small vertical shaft b³, upon which is supported a wheel b⁴, having vanes 60 or blades and so placed that it extends under the downwardly-projecting end of the pipe b in a position to be rotated by fluid flowing therefrom.

The pipe B has at a point near the tank A 65 a section D made of heavy stoneware, porcelain, or other electrically non-conducting material, said pipe having suitable flanges d for attachment to said section. In order that this section may not be injured by the expansion and contraction of the pipe B, we provide an expansion joint or coupling E, into which the said pipe extends. This joint consists, primarily, of a part e, screwed or otherwise attached to the pipe B and provided 75 with a stuffing-box having a section e', into which the end portion of the pipe B enters.

The insulating-section D and the expansion joint or coupling E are both inclosed in a length of terra-cotta or stoneware conduit F, 80 so that the earth in which the pipe B is laid is kept from contact therewith in the immediate vicinity of the insulating-section. From an inspection of this construction it will be seen that should lightning strike any part of 85 the tank A there will be no low-resistance path for the discharge to pass to or from the pipe B, with consequent injury to the same, on account of the fact that said pipe is electrically insulated not only from the bottom 90 of the tank by the insulating-blocks b², but also, by means of the section D, from the greater part of the piping system and grounds adjacent thereto. Said pipe B is, moreover, further insulated from the metal of the tank 95 by the rings a' and is thereby protected from possible injury should the tank be struck by lightning. Upon the ignition of the oil in the tank carbonic-acid gas mixed with a certain proportion of liquid is forced 100 from the generating apparatus C through the pipe B and the branch pipes b, so that it

strikes the inclined wheels b^4 and causes them to rapidly rotate. Such action distributes or scatters the liquid or gas flowing from the pipe B over the entire surface of the burning oil, thus tending to quickly smother the flames and extinguish the fire.

We claim as our invention—

1. The combination of a tank having an opening into it, a pipe extending from said opening to a point above the normal level of liquid in the tank, a source of supply for fire-extinguishing fluid and a pipe connecting said source with the tank, said pipe extending through the said first pipe into the tank, with means for electrically insulating the second pipe from the tank, substantially as described.

2. The combination of a tank, a source of supply for fire-extinguishing fluid, a pipe connecting the tank and the source of supply, the same having a plurality of branches provided with outlets placed to discharge into the tank, with means for supporting said branches, said means being electrically insulated from the tank, substantially as described.

3. The combination of a tank, a source of supply for fire-extinguishing fluid, a pipe connecting the said source and the tank, an insulating-section in said pipe and an insulating-conduit surrounding the said section and the pipe in the immediate vicinity of the same, substantially as described.

4. The combination of a tank, a source of supply for fire-extinguishing fluid and a pipe connecting the same with the tank, said pipe being electrically insulated from the tank and having a plurality of branches provided with outlets placed to discharge into the tank,

bars for supporting said branches and insulating material whereby said bars are kept from electrical contact with the tank, substantially as described.

5. The combination of a tank, a source of supply for fire-extinguishing fluid, an opening into the tank having a conduit extending from it above the level of fluid in the tank, a pipe connecting the source of supply with the tank and extending into said opening and through said first pipe, with insulating material in the first pipe for preventing electrical contact between the same and the second pipe, and an outlet or outlets in the second pipe placed to discharge into the tank, substantially as described.

6. The combination of a tank, a source of supply for fire-extinguishing fluid, an opening into the tank having a conduit extending from it to a point above the level of fluid in the tank, a pipe connecting the source of supply with the tank, said pipe extending into said opening and through said conduit, with insulating material in the conduit for preventing electrical contact between the same and the pipe, and an outlet or outlets to said pipe placed to discharge into the tank, said outlets being provided with revoluble means for distributing fluid discharged therefrom within the tank, substantially as described.

In testimony whereof we have signed our names to this specification in the presence of two subscribing witnesses.

THOMAS M. COLLISON.
